AUTOMATIC SWITCH FOR USE IN TELEPHONE OR LIKE SYSTEMS

William George Patterson and Ernest Jules Gachet, London, England, assignors to Siemens Brothers & Company Limited, London, England

Application March 7, 1932, Serial No. 597,142,
and in Great Britain March 17, 1931

10 Claims. (CL 179—27.51)

This invention relates to selecting switches for automatic telephone and other selective systems and has mainly in view an improved form of one-motion step by step selecting switch, although certain features of the invention are applicable also to two-motion switches.

According to the present invention the switch together with its control relay or relays is constructed as a single unit. The switch comprises a plate supporting a step by step mechanism, a driving magnet, and a control relay or relays. The magnet and the relay or relays may be mounted on one side of the plate and the step by step mechanism on the other. The plate may be of channel shape or may be a die-casting including fixing details, etc. The step by step mechanism includes a rack.

The present invention is particularly applicable to a switch in which the rack member carries wipers which are adapted to enter a bare wire multiple, but the rack member may serve to produce a rotary movement of wipers over bank contacts.

For the control of ordinary one-motion selecting switches a pair of relays is required, one which when operated sets the switch in motion and the other is used as a test relay to stop the motion of the switch on a desired outlet being reached. In the ordinary subscriber's preselector, for instance, these relays are the line and test (or cut-off) relays, the line relay starting the switch in motion and the test relay stopping the motion or on incoming calls disconnecting the line relay.

A feature of the switch of the present invention is that in a one-motion switch the driving magnet itself acts as a line relay. When the switch is used as a searching switch it is arranged however that the magnet on energizing gives the rack member a single step whereupon a cam surface on the rack operates on a member which disconnects the starting circuit and closes a local driving circuit. Obviously it may be arranged that the magnet armature need not move to its full extent before the local circuit is closed. An early make contact controlled by the armature may be used to assist in the closing of the local circuit.

It is arranged that the switch is self restoring in that the rack is returned to normal by a spring. In this arrangement the test relay may be employed as a retaining magnet. It is then arranged that on operating it inserts a retaining pawl into engagement with the rack. The usual retaining pawl is furthermore disengaged

from the rack on operation of the test relay and kept disengaged despite the subsequent release of the test relay until the rack is at normal. A convenient way of arranging for this is to form the pawl as a spring member with a twist 60 in it so that it may press downwardly and also be movable to one side. The moving may be effected by the test relay armature through an intermediate member if necessary and when moved it may spring down at the side of the 65 rack and be lifted back by means of a ramp to re-engage the rack as the normal position is being reached. The driving magnet pawl is preferably normally out of engagement with the rack and drops in after slight movement of the 70 armature.

The withdrawal of the holding detent may also be caused by a projection on the rack operating on the intermediate member (say a bell crank) when congestion or last contacts are 75 reached, in which case the test relay need not be operated on congestion occurring or the last contacts being reached.

A further feature of the switch is in connection with the feed to the wipers where the rack 80 member carries the wipers. The rack may bear at its rear end a block of insulating material which carries metal strips that are connected to the wipers. With the strip connected to the test wiper a stationary wiper is always in contact. Spring contacts are brought into contact with the remaining strips when the test relay operates.

In connection with the local driving circuit, this must be opened when the test relay operates 90 and not reclosed whilst the rack returns to normal. To produce this sequence of operations we may provide a spring with a twist in it. Normally the spring may press on a contact and be moved side ways by a cam surface on the rack 95 to engage a contact in the local driving circuit once the switch starts. When the test relay operates the spring is lifted by an extension of the armature of the relay clear of the contact and clear of the cam surface so that under its own tension it moves sideways onto the top of the cam surface thus preventing further closure of the local driving circuit. On return of the rack to normal a sinking of the cam surface may provide for the return of the spring to its normal position. A second similar spring may be provided which is underneath and coupled to the first by an insulating block. This spring may form part of a make-before-break circuit, a contact plate on the extension of the armature op- 100 105 110

erating on a pin attached to the spring to lift the spring from a fixed contact. It may be provided that the fixed contact is only touched by the second spring when the rack member has left normal.

5 The switch when used as a subscriber's line switch may be provided with off normal contacts which when operated apply a busy condition to the subscriber's line at the final switching stage.

10 The accompanying drawings illustrate by way of example the features of the present invention applied to a switch employing a longitudinal rack member for operating the wipers, the electromagnets being secured to one side of a common mounting plate whilst the rack member is mounted on the other side of the plate the armature of the electromagnets passing through the plate.

15 In the drawings Fig. 1 illustrates a circuit arrangement employing a switch according to the present invention. Figs. 2, 3 and 4 illustrate side, plan and end views respectively of the general mechanical arrangement of the switch, whereas Figs. 5 and 6 give enlarged side and plan views respectively of the stepping mechanism and the retaining pawl arrangements and several other details of the switch.

20 The circuit arrangement shown in Fig. 1 will first be described as this will enable the mechanical arrangements subsequently described in connection with the other figures to be more clearly understood.

25 In Fig. 1 the portion marked LS is the line switch comprising wipers W+, W-, WP and WM, the stepping magnet MC, the multiple field LSB, and testing relay T. The wipers normally stand out of the bank.

30 Associated with the switch are contacts MC1, MC2, MC3 and MC4. Of these contacts MC1 change over when the wiper shaft takes its first step, but however the intermechanical arrangements of the switch are such that when the test relay T operates the contacts are entirely broken away from each other until the wiper carriage is restored to normal. The contacts MC2 also have a peculiar operation, in that they remain in the normal position shown until the test relay T operates whereupon they operate and change over and remain operated until the test relay is released whereupon the three contacts are entirely disconnected from each other until the wiper carriage is returned to normal where they are again restored to their normal position as shown.

35 The contacts MC3 open when the wiper shaft takes its first operating step and the contacts MC4 are operated directly on the energization of the electromagnet.

40 The test relay T has three contacts t_1 and t_2 being of the change over type normally making with back contacts but making with the wipers W+ and W- when operated, whereas contact t_3 is of the ordinary make type connecting up the circuit of the wiper WM when operated.

45 The portion CC of Fig. 1 represents a cross connection field interposed between the line switches and the final selectors FS, the circles representing terminal blocks and the intermediate lines, jumper wires. The subscriber's line L is connected to the terminal block associated with the final selectors FS. Associated with each subscriber's line is a meter M, the connections to which are designated MW, and MR.

50 The speaking wires are designated positive and negative, and the private or test wire P.

The stepping magnet receives its initial energizing circuit over the subscriber's line, but after the first step of the wiper shaft and the operation of the contacts MC1 the magnet derives its stepping impulses from the interrupter INT.

55 Considering the circuit in detail, when the subscriber removes his receiver a loop is placed across the two wires of the line L and the following circuit is completed, earth, contact t_1 , positive wire, subscriber's loop, negative wire contacts t_2 and MC1, stepping magnet MC to battery and earth.

60 Almost simultaneously with the energization of magnet MC contacts MC4 close and apply earth to the magnet whereby it is held energized independent of the subscriber's loop.

65 The energization of magnet MC causes a pawl to operate and advance the wiper shaft by one step. On the advance of the wiper shaft contacts MC1 change over and contacts MC3 break. Contacts MC1 disconnect the original energizing circuit of the magnet MC, and apply thereto an interrupted earth from the interrupter INT. The wiper shaft is thus advanced step by step, the wiper WP being brought into successive connection with the contacts of test or private wire leading to the succeeding switching stage.

70 The contacts MC3 on opening disconnect the test potential from the final selector and thus render the calling line busy to incoming calls.

75 A free outlet to a succeeding switching stage is characterized by a battery on the test wire and when the wiper WP meets a free outlet the test relay T operates from earth contacts MC2 normal the lower high resistance coil (II) and upper low resistance coil (I) of relay T.

80 When relay T operates contacts t_1 and t_2 open points in the original operating circuit of magnet MC and connect the positive and negative wires through to the succeeding switching stage.

85 Contacts t_3 connect the meter M to the wiper WM over the wire MW in preparation for the operation of the meter.

90 On the operation of relay T the contacts MC1 are entirely disconnected from each other thus opening any possible circuit of magnet MC. Likewise the contacts MC2 are changed over, the bottom high resistance coil (II) of relay T thus being disconnected and an earth applied direct through the upper low resistance coil to the wiper WP. This latter earth renders the outlet to the succeeding switching stage non-selectable to other searching line switches, whereas relay T is held to the battery on wiper WP.

95 The operation of relay T also causes a detent normally engaging the teeth of the wiper shaft to be disengaged therefrom and a temporary detent is inserted which holds the shaft whilst the switch is engaged, the normal detent being rendered immune from any possible re-engagement with the teeth of the wiper shaft until the wipers have been returned to normal.

100 The call to the wanted subscriber may now proceed in well known manner, and when the wanted subscriber replies a battery is applied to the wiper WM, over contacts t_3 , wire MW, meter M, wire MR to earth. The meter operates and registers the call against the calling subscriber.

105 When the calling subscriber replaces his receiver at the termination of the conversation the battery on the wiper WP is removed and

relay T releases. On the release of relay T the temporary detent is disengaged from the wiper shaft which thereupon restores to its normal position under spring pressure. Further, immediately relay T releases the contacts MC2 entirely break from each other so that there is no circuit for relay T during the homing of the switch.

When the wiper shaft reaches its normal position the contacts MC1, MC2, MC3 are returned to their normal positions, as shown.

If the switch is unable to find a free outlet to the succeeding switching stage, the switch wipers are advanced to their ultimate positions and contacts MC1 which in the case of finding a free line were operated by the relay T are now operated mechanically and the normal detent holding the wiper shaft is mechanically tripped out and the wiper shaft returned to its normal position. If no special provision is made to prevent the wiper arm from again being advanced, it continues to pass in and out of the bank until a free outlet is found.

When the subscriber's line is seized from the final selector FS a battery is applied to the wire P which battery passes over contacts MC3, coils (I) and (II) of relay T, contacts MC2, to earth. Relay T operates and at contacts t1 and t2, disconnects the circuit of magnet MC and prevents the switch from being operated. Arrangements are provided to prevent the operation of relay T in this case effecting contacts MC1 and MC2.

Turning to Figs. 2 to 6, the components of the switch are mounted on a longitudinal stamped or cast metal frame 1 provided at either side with turned over edges, the edges continuing beyond one end of the frame to form fingers 2 and 3 by which the switch is supported in position on the rack carrying the multiple banks. Electromagnets 4 and 5 provided with cores 6 and 7 and yokes 9 and 8 respectively are secured to the frame 1 by screws passing through the frame and engaging the yokes 8 and 9 or vice versa, as shown at 10.

On the top of the frame adjacent to fingers 2 and 3 is a terminal block 11 adapted to engage a jack on the supporting frame to provide the electrical connections to the switch.

The wiper carrying shaft 14 is supported by a U-shaped metal piece 12 secured to the frame 1 by screws 13. The shaft comprises a longitudinal T-shaped member, the edge of the trunk of the T being provided with teeth to form a rack.

The cross arm of the wiper shaft 14 lies between the parallel limbs of the U-shaped piece 12, the ends of the limbs being slotted and grooved to partially embrace the cross arm but allowing longitudinal movement thereof.

The shaft is shown carrying two sets of wipers 15 and 16 each set comprising two wipers separated by insulating material, the insulating material being riveted or otherwise secured to a limb of a bifurcated bracket 17 which in turn is secured to the wiper shaft in any suitable manner.

A screw 18 passes through the wiper and shaft and serves to hold one end of a restoring spring 19, the other end of the spring being held by a screw 20 engaging the frame 1.

The electromagnet 5 is provided with an armature 21 having brackets 22 at rightangles, one at either side thereof. A pivot pin 23 passes through the brackets 22 and is held in position

by a claw 24 secured to a metal piece 25 attached to the yoke 8 by screws 26 and 27. A coiled spring 28 normally maintains the armature away from the end of core 7.

Secured to the armature 21 is an arm 29 which is bent over at rightangles at its end to support a leaf spring 30 carrying a pawl 31, the latter when operated being adapted to engage the teeth of the rack on the wiper shaft 14. Also to the same end of the arm 29 is secured a pin 32 adapted to normally maintain open the contact springs 33 which are supported by brackets 34 secured to the frame 1.

A bracket 35 forming part of piece 12 is bent up at rightangles to the base portion thereof and is bifurcated at its end, the fingers being so bent that one 35a is disposed in front of and over the pawl 31, whilst the other finger 35b is beneath the pawl. These two fingers serve to guide the pawl in its operative and retractive movements.

The normal retaining pawl 36 is riveted to a leaf spring 37 secured to a bracket 38, which bracket is attached by screw 39 to a further turned up portion of piece 12. The leaf spring 37 is twisted so that its two parts are substantially at rightangles to each other, thus allowing movement in two directions, the pawl 36 being attached to the horizontal part of the spring.

The operation of the parts of the switch just described is as follows:

When the electromagnet 5 is energized the armature is rotated about the pivot pin 23 and moves to the left carrying with it the arm 29, spring 30, and pawl 31. The pawl rides below the upper finger 35a of the bracket 35 and is thereby guided into engagement with the first tooth of the rack on the wiper shaft. During the continued forward movement of the pawl the wiper shaft is pushed forward (to the left) one step against the tension of spring 19.

The normal retaining pawl 36 rides over teeth in the rack as the shaft moves forward and when each complete step is taken engages a next tooth in the rack and prevents the return of the wiper shaft. When the arm 29 moves to the left the pin 32 moves with it and allows the contact springs 33 to make contact. When the electromagnet 5 de-energizes the armature 21 and arm 29 move to the right, the pawl 31 being guided by the under finger 35b of the bracket 35 out of engagement with the rack. On the return of arm 29 to normal the contact springs 33 are again broken. It will be seen that the electromagnet 5 corresponds to stepping magnet M in Fig. 1, and contact springs 33 to contacts MC4.

Continuing with the description, the electromagnet 4 is provided with a bell crank armature 40, pivoting round a pin held in a bracket embracing the yoke 9 in known manner. The armature is provided with an adjusting screw 41 opposite the core 7. Continuing parallel with the vertical part of the armature is an arm 42, being secured thereto by screws, the arm being L-shaped so as to pass round and over the top of the wiper shaft. The free end of the arm is turned round at rightangles and inclined from the horizontal. A temporary retaining leaf spring pawl 43 is screwed to this inclined part of the arm 42 and is maintained at such an angle as to engage the teeth in the rack of the wiper shaft 14 when moved to the left.

The arm where it is bent over on to the top of the wiper shaft is adapted to engage one arm of a bell crank lever 45 pivotally attached to a bracket 46 which bracket in turn is screwed to the frame 1. The other arm of the bell crank lever is positioned opposite the leaf spring 37 carrying the normal retaining pawl 36.

Before explaining the function of the horizontal arm of the bell crank armature 40, the arrangement of the contact springs will be described.

Attached beneath the end of the wiper carrying shaft 14, at the opposite end to that carrying the wipers 15 and 16, is a block 47 of insulating material and stretched along the length of and over the bottom of this block are four stout feeder wires 48, the wires being terminated at two little blocks 49 and 50 attached to or integral with the block 47. The wires are taken through holes in the blocks, over the top of the blocks, and then through further holes. These feeder wires are provided for the electrical connections to the pairs of wipers 15 and 16, further wires being connected to the wires and led along one side of the cross arm of the T-shaped wiper shaft, the wires being covered by a channel 51, which channel is shown V-shaped.

Situated beneath each one of three of the feeder wires 48 is a pair of contact springs 52 and 71, the upper spring of each pair being provided with a lip 53. Each pair of contact springs is adapted to normally be in electrical connection but when operated the upper spring with the lip rises breaking connection with its bottom spring 71 and the lip 53 makes connection with its appropriate feeder wire 48. A fourth contact spring 54 is provided which permanently makes contact with the fourth feeder wire. The contact springs are secured into an insulating block 55 attached to the frame 1.

At one side of the insulating block 47 is a bridge 56 extending along the length of the block.

A bracket 57 secured to the frame 1 carries an insulating block 58 which supports contact springs 59 and 60. A contact 77 for making a through connection also being supported. These contact springs are bent at right-angles along their length so that they are allowed movement in the two directions, that is, sideways and upwards. The contact springs are secured together at their free ends by an insulating piece 69, the insulating piece being provided with a projection 70 normally adapted to register with the insulating block 47 in front of an inclined surface of the bridge 56 thereon.

The ends of the contact springs are spoon shaped, the upper spring 59, in its lateral movement being adapted to make contact with one or other of the fixed contacts 61 or 62. The lower spring 60 makes connection wholly throughout its lateral movement with fixed contact 63. The fixed contacts 61, 62 and 63 are supported in an insulating block 64 secured to the frame 1. In operation the springs 59 and 60 are first moved laterally, the spring 59 passing from contact 61 to contact 62, after which lateral movement the springs are moved upward to entirely break contact with the fixed contacts.

Referring now to the horizontal arm of the bell crank armature 40, this arm is provided with an extension arm 65, bent upwards at right-angles. The arm 65 is apertured to decrease

weight and is bifurcated at its free end, an insulating block 66 bridging the two limbs. The block 66 is adapted to be disposed over and press on to the upper contact springs of the pairs of springs 52 and thereby normally maintain the pairs of springs in contact. Also at the point where the extension arm 65 is bent upwardly at right angles is secured a further insulating block 67 carrying a small contact piece 68.

The contact piece 68 is disposed below but not normally in contact or alignment with a metal pin 72 in electrical contact with spring 60. The inner edge of the contact piece 68 is turned up slightly so that when in electrical connection with pin 72, the pin is prevented from sliding off.

To the extremity of the frame 1 is attached a pair of contact springs 74 normally maintained in contact by the pressure of the end of the wiper shaft 14.

From the cross arm of the T-shaped wiper shaft just behind the rack in the trunk thereof, projects a pin 75. This pin represents the ultimate operative position of the switch and when such a position is reached the pin 75 registers with one arm of the bell crank lever 45.

The operation of the items just described will now be explained.

It will be remembered that the wiper shaft 105 has previously been described as being stepped by the magnet 5, the wipers 15 and 16 thereby being stepped into the bank, the magnet 5 corresponding to stepping magnet MC and the contact springs 33 to contacts MC4 in Fig. 1.

The magnet 4 corresponds to test relay T, Fig. 1, the contact spring 59 and fixed contacts 61 and 62 to contacts MC1, the contact spring 60, fixed contact 63, pin 72, and contact piece 68 correspond to contacts MC2, contact springs 58 115 to contacts t1, t2 and t3, spring 54 to the connection between the wire P and the wiper WP, and the contact springs 74 to contacts MC3.

When the wiper shaft takes its first step, the bridge 56 on the block 47 moves forward and the projection 70 rides on to the top of the bridge piece 56 and as a consequence the insulating piece 69 and the contact springs 59 and 60 are pushed outwardly. The contact spring 59 moves from fixed contact 61 to contact 62, 120 bridging the two contacts during a portion of its travel. The spring 60 slides over the surface of fixed contact 63, but does not break connection therewith, and the pin 72 attached to spring 60 moves over the top of, and in alignment with contact piece 68, but does not make contact therewith.

Also on the first step of the wiper shaft the two contact springs 74 break from each other. It will be remembered that when the relay 135 T Fig. 7 operates the contacts MC1 are entirely disconnected from each other whilst the contacts MC2 are changed over.

When the wipers meet a free outlet to the succeeding switching stage the magnet 4 is energized and the armature 40 attracted.

The extension arm 65 moves upward whilst arm 41 moves to the left.

When the extension arm 65 moves, the contact springs 52 are released and allowed to move upward, breaking connection with their lower contact springs 71 and making connection with the feeder wires 48, which as will be remembered in connection with Fig. 1 disconnects the 145

original operating circuit of relay M and connects up the speaking wires to the wipers.

Also the contact piece 68 moves upwards carrying with it the pin 72 and contact springs 59 and 60. The springs 59 and 60 break connection with their fixed contacts, the electrical connections through spring 59 being entirely disconnected whilst electrical connection is made between the contact piece 68 and the spring 60. The springs 59 and 60 are tensioned downwards and inwards, but whilst the armature 40 is operated the springs are prevented from moving inwards by the turned up part of the contact piece 68, which inward movement would be allowed by the pin 70 being moved above the bridge piece 56 on the operation of the armature.

Turning now to the arm 42, when this moves to the left, the temporary retaining pawl 43 is inserted into a tooth of the rack on the wiper shaft, almost simultaneously with which operation the arm strikes one arm of the bell crank lever 45. The latter rotates and encounters the spring 37 carrying the normal retaining pawl 36 and pushes the pawl out of engagement with the rack. By reason of the tension in the horizontal part of the spring 37 the pawl 36 slips down to the side of the rack, the wiper shaft being prevented from restoring by the temporary retaining pawl 43.

The switch remains in this position until magnet 4 is released at the termination of the engagement of the switch.

When the switch is released magnet 4 de-energizes and the armature 40 restores. The temporary retaining pawl disengages the rack of the wiper shaft and this shoots back to normal under the tension of spring 19.

When the arm 65 moves downwards the contact piece 68 breaks connection with the pin 72 and consequently with the spring 60.

When the armature 40 restores the contact piece 68 moves downwardly, and by reason of the lip on the contact piece moving out of the way of the pin 72 the springs 59 and 60 move sideways and the projection 70 on the block 69 clips over on to the upper surface of the bridge 56, thereby preventing the downward restoration of the springs whilst the wiper shaft is off normal.

The contact springs 59 and 60 are thus held in their upward position during the restoration of the wiper shaft by reason of the projection 70 bearing on the upper surface of bridge 56, but when the switch reaches normal the projection slides off the bridge, allowing the springs to restore.

Further at the side of the rack to which the retaining pawl 36 is pushed by the bell crank lever 45 is a cam 76 corresponding in position to the normal position of the wiper arm. Thus when the wiper shaft restores the cam slides under the pawl 36 and pushes it upwards, the pawl thereupon being forced into a tooth by the lateral tension of springs 37.

If the switch is stepped to its ultimate position without magnet 4 energizing the pin 75 strikes one arm of the bell crank lever 45 causing this to rotate and force the retaining pawl out of engagement with the rack on wiper shaft 14. Also a ramp on the bridge piece 56 is so disposed as to engage pin 70 when the wiper shaft is stepped from its penultimate to its ultimate position. The effect of the ramp is to raise springs 59 and 60 out of engagement with

their respective fixed contacts 61, 62 and 63, thus simulating the operation of armature 40. The wiper shaft thereupon restores to normal under the tension of spring 19, and when the shaft reaches its normal position the pawl 36 is again guided into engagement with the rack by cam 76, as before described.

It is to be understood that many modifications may be made to the details comprising the switch without departing from the spirit of the present invention.

For example, an arcuate bank may be employed, the wipers being pivoted so as to rotate round the bank. The wiper shaft will engage a slot in the wipers so that although the shaft moves along the same straight line the wipers will be pushed so as to rotate through the necessary arc.

Further the feeder wires 48 may be replaced by flat metal strips moulded into the block 47 and the little blocks 49 and 50 dispensed with, the strips being provided with means for soldering wires thereto.

What we claim as new and desire to secure by Letters Patent is:

1. An electromagnetic step-by-step switch having a common frame, a wiper carrying element mounted on said frame, a pair of magnets mounted on said frame, means operated by one magnet for operating the wiper element step by step, means for holding the element in advanced position at certain times, and means controlled by the other magnet for holding the element in advanced position at other times.

2. A step-by-step switch having a wiper carrying element, means for advancing the element, a mechanical detent for holding the element in advanced position only during its advancement, another detent, and an electromagnet for operating said other detent to engage the element simultaneously with or just prior to the disengagement of the mechanical detent.

3. A step-by-step switch having a wiper carrying element, means for advancing the element, a mechanical detent normally holding the element in advanced position, a temporary detent, an electromagnet, and means operated by the magnet for removing the mechanical detent and causing the temporary detent to engage and hold the element in advanced position.

4. A step-by-step switch having a wiper carrying element, means for advancing the element, a mechanical detent normally holding the element in advanced position, a temporary detent, an electromagnet, and means operated by the magnet for removing the mechanical detent and causing the temporary detent to engage and hold the element in advanced position, said mechanical detent carried on one end of a leaf spring twisted at right angles to itself at a point along its length so that the end carrying the detent is movable in two places.

5. A step-by-step switch having a wiper carrying element, means for advancing the element, a mechanical detent normally holding the element in advanced position, a temporary detent, an electromagnet, means operated by the magnet for removing the mechanical detent and causing the temporary detent to engage and hold the element in advanced position, and means controlled by the element when moved to its ultimate position for disengaging the mechanical detent from the element.

6. In a step-by-step switch having a wiper carrying element, and means for advancing the

element to cause the wiper to pass over contacts, circuit controlling contact springs, an electromagnet having means for controlling the switch operation, said springs controlled both by the 5 position of the element and by the magnet.

7. In a step-by-step switch having a wiper carrying element and means for advancing the same, a set of springs having movement in two planes, a magnet, means on the element for moving the springs in one plane and means controlled by the magnet for moving the springs in 10 the other plane.

8. In an electromagnetic step-by-step switch, wipers, a wiper carrying element, an electromagnet for partially controlling the operation of the element, said element and magnet mounted on a common frame, contact springs controlling the connection of the wipers to external circuits, said springs operated by said 15 magnet.

9. An electromagnetic step-by-step switch having wipers, a magnet having means for mov- 20

ing said wipers, a subscriber's line connected to the switch, a circuit for energizing the magnet including the line, and means controlled by the initial energization of the magnet over the line for closing another circuit for the magnet in- 80 dependent of the loop.

10. An electromagnetic step-by-step switch having wipers and a magnet for moving the wipers, a subscriber's line loop, a circuit for energizing the magnet over the loop, a source of intermittent potential, means operated by the first step of the wipers for disconnecting the magnet from the loop and connecting it to the intermittent source, said magnet operated thereafter from said source until an idle trunk 85 is found by the wipers, and means operated when such idle trunk is found for disconnecting the magnet from the intermittent source and maintaining the original circuit for the magnet open until the switch is released. 90
